(57) **CLAIM**

The ornamental design for a wine aerator and pourer, as shown and described.

DESCRIPTION

FIG. 1 is a perspective view of a wine aerator and pourer showing the new design.

FIG. 2 is a front view of the wine aerator and pourer of FIG. 1.

FIG. 3 is a rear view of the wine aerator and pourer of FIG. 1.

FIG. 4 is a side view of the wine aerator and pourer of FIG. 1.

FIG. 5 is an opposite side view the wine aerator and pourer of FIG. 1.

FIG. 6 is a top view the wine aerator and pourer of FIG. 1; and,

FIG. 7 is a bottom view the wine aerator and pourer of FIG. 1.

The dash-dash broken lines in the figures depict portions of the wine aerator and pourer that form no part of the claimed design.

1 Claim, 7 Drawing Sheets
